UNITED STATES PATENT OFFICE.

OSCAR MUSSINAN, JR., OF NEW YORK, ASSIGNOR TO EBERHARD FABER,
OF PORT RICHMOND, N. Y.

METHOD OF UNITING TUBES.

SPECIFICATION forming part of Letters Patent No. 350,075, dated September 28, 1886.

Application filed March 25, 1886. Serial No. 196,598. (No model.)

To all whom it may concern:

Be it known that I, OSCAR MUSSINAN, Jr., a citizen of the United States, residing at New York, in the county and State of New York, 5 have invented new and useful Improvements in Methods for Uniting Tubes to Each Other, of which the following is a specification.

This invention relates to a method of uniting tubes to each other, which is hereinafter 10 described and claimed, reference being had to the accompanying drawings, in which—

Figure 1 shows a metal blank for the inner tube. Fig. 2 shows an inner and an outer tube united to each other, and Fig. 3 is a cross- 15 section on the line $x-x$ of Fig. 2. Figs. 4, 6, and 8 represent modifications of the invention. Fig. 5 is a cross-section on the line $y-y$ of Fig. 4. Fig. 7 is a cross-section on the line $z-z$ of Fig. 6. Fig. 9 is a cross-section on the line 1 1 of Fig. 8. Fig. 10 shows a blank for the inner tube, having its hole B in the position required for the modifications shown in Figs. 8 and 9. Fig. 11 shows a press and suitable dies for uniting the tubes. Fig. 12 is a vertical section on the line 2 2 of Fig. 11. Fig. 13 is a vertical section on the line 3 3 of Fig. 11.

Similar letters indicate corresponding parts.

The invention is applied in the present example to pen-holders whose outer tubes contain an inner tube or nib which is required to be united to the outer tube in such a manner that the tubes shall be fastened to each other; but I do not restrict its application to that class of tubes, as it can be used, generally, 30 in tubes of thin or sheet metal. The inner tube or nib, A, is made from a sheet-metal blank, (shown in Fig. 1,) which is cut out in proper form for that purpose, the hole B being punched out in the same operation. The blank thus prepared is then bent into tubular form, its edges being left unclosed, so that it has a slit, C, extending throughout its length. The tube A is inserted in the outer tube, D, 35 and is secured thereto by forcing into the hole B a portion of the outer tube, which overlies said hole in such a manner that the portion of the tube D which enters said hole engages and interlocks with its edge, so that the tubes 40 come securely fastened to each other. This

is accomplished by means of a press, E, provided with a male die, F, of suitable form, and a female die, G, formed on a mandrel, M, adjustably secured in the press. The tubes A and D are placed on the mandrel M in such a 55 position that the hole B of the inner tube, A, will come directly over the female die G. The male die F is then pressed down upon the outer tube, D, with force sufficient to press its side down through the hole B of the tube A at H, 60 Figs. 2 and 3, far enough to engage the sides of the opening and to enter the female die, whose bottom will resist the pressure and cause the projecting portion of tube D to expand and interlock with the edge of the hole. 65 Fig. 2 and its cross-section, Fig. 3, show the inner and outer tubes interlocked by means of the dies F G in this manner, the interlocking depression at H and hole B being elongated, so as to prevent the tubes from turning on each 70 other, as well as from having endwise motion.

In Fig. 4 and its cross-section, Fig. 5, the interlocking device shown in Figs. 3 and 4 is combined with an interlocking device consisting of indentations and projections I and J, 75 produced in the inner and outer tubes from within outward without making openings in the metal, the operation being performed by means of a suitable press provided with a male die, K, which is placed inside of the inner 80 tube, on which die the tubes are pressed by a descending female die, L, whose descent causes the male die to make indentations and projections which engage with each other in both tubes. The press here shown is also provided 85 with such dies K and L, so that all the dies F G and K L can be simultaneously operated and the tubes be united by means of the combined devices here shown.

The forms of the dies and their relative positions can be changed to suit the taste and judgment of the manufacturer.

In Figs. 4 and 5 the locking devices shown are in positions which correspond to the positions of the dies in the press, Fig. 11. In 95 Figs. 6 and 7 indentations I and projections J are arranged on both sides of and in line with the locking device H B. In Figs. 8 and 9 an indentation I and projection J are between two locking devices, H B.

Fig. 10 represents a metal blank provided with two holes, B, such as will be required in carrying out the form of the invention shown in Figs. 8 and 9.

5 What I claim as new, and desire to secure by Letters Patent, is—

1. The method of interlocking tubes one upon another by placing one inside the other, and then producing indentations I and projections J thereon, extending from within outward, interlocking with each other and pressing a portion of the outer tube into a hole, B, formed in the inner tube, substantially as described.

15 2. Two or more tubes placed one within the other and provided with indentations I and projections J, made in their sides, extending in

an outward direction and interlocking with each other, combined with a projection or projections, H, pressed from the outer tube inwardly into a hole, B, formed in the inner tube, substantially as shown and described.

20 3. The combination of the inner tube having the hole B with the outer tube formed with the unbroken projection H, pressed into said hole and interlocked therewith, substantially as described.

25 In testimony whereof I have hereunto set my hand and seal in the presence of two subscribing witnesses.
